UNITED STATES PATENT OFFICE

RICHARD ADAM, OF FRIEDENAU, GERMANY.

BUNSEN BURNER FOR LIQUID HYDROCARBONS.

SPECIFICATION forming part of Letters Patent No. 643,097, dated February 13, 1900.

Application filed May 1, 1899. Serial No. 715,190. (No model.)

To all whom it may concern:

Be it known that I, RICHARD ADAM, a citizen of the Kingdom of Prussia, and a resident of Friedenau, near Berlin, in the Kingdom of Prussia and German Empire, have invented 5 certain new and useful Improvements in Bunsen Burners for Liquid Hydrocarbons, of which the following is a specification.

The object of the present invention is a new 10 and improved Bunsen burner for liquid fuel in which the blue flame is produced without the employment of chimneys or the like only by means of jets of steam acting as injectors and blowing a strong current of air into the 15 flame in order to produce the Bunsen flame. The steam is generated without the employment of a separate auxiliary flame.

The burner is especially adapted for cooking and heating purposes. 20 In the accompanying drawings, Figure 1 is a vertical section through the axis of the burner. Fig. 2 shows a modified form of the upper part of the same.

The grating on which the cooking vessel 25 rests is omitted in the drawings because its form is of no importance for the present invention.

1 is a receptacle for the liquid fuel—for example, kerosene.

30 2 is the wick, tipping with its lower end into the containings of vessel 1 and lying bare at its upper end.

3 is the inner wick-tube, passing right through the receptacle 1, whereas 4 signifies 35 the outer wick-tube.

5 is a water-basin of annular form surrounding the reservoir 1. It communicates by means of a tube 6 freely with a vertical tube 7, arranged in the center of the inner wick-tube 3. The same is open at its top and serves for inserting the most essential part of 40 the whole arrangement—viz., the evaporator-tube 8, closed at its top and at its lower end by means of a disk 9 and divided by means 45 of two other disks 10 and 11 into three unequal chambers, the middle one, 13, serving for raising steam, the upper one, 12, for superheating the same, and the lower one, 14, which is the largest of all, for collecting the 50 steam. Nozzles 15, directed toward the upper end of the burner, allow the steam to es-

cape under rather strong pressure, thereby producing a strong current of air to the flame.

Pipes 17 lead from the partition-disk 10 through disk 9 into the central water-basin 7. 55 Wicks 16 are passed rather tightly through them, ending freely in the middle chamber 13 and serving for bringing water to this part of the apparatus.

The heat of the flame, acting on the outer 60 surface of tube 8, evaporates the water, and the steam thus produced passes by means of a series of holes 18 into the chamber 12, where it is superheated by the hot walls. From here it passes through a small pipe 19 into the 65 steam-collecting chamber 14, where it is freed from any adhering water.

In the lower part of chamber 14 the tubes 17 are provided with perforations 20, through which the condensed water is sucked by the 70 wicks 16. It is therefore impossible that the level of the condensed water reaches the nozzles 15 and chokes them.

On the evaporating-pipe 8 is arranged a removable flame-spreader 23, which serves to 75 transmit the heat of the flame to the tube 8 and to direct it over the whole surface of the same, especially to its lower part. It may be fixed to the tube in different ways. For example, the disk 23 may be fixed to a tube 21, 80 closed at the top and fitting exactly over the tube 8, ears 22, also fixed to the same and bearing against the inner wick-tube 3, serving for centering the whole device.

In the modified form (represented by 85 Fig. 2) the disk 23 is fixed to a short tube 25, open at both ends and fitting exactly over the tube 8. Concentrically to the same is arranged a second short tube 24, provided near its upper end with a series of perforations, 90 the tube fitting exactly into the inner wick-tube 3.

In order to trim the wick, the flame-spreader 23 is simply withdrawn from the evaporator 8. When it is replaced, the upper end of the 95 wick is ignited and burns with a white flame until the generation of steam begins under the influence of the heat developed by it. As soon as blue streaks appear in the flame the wick 2 is screwed higher until the flame appears perfectly blue. The wick burns only 100 on its outer surface. The steam blown into

the flame has no action at all on the same, but serves only to produce the current of air necessary for the production of the blue flame. It is evident that any other liquid—
5 for example, alcohol, a mixture of water and alcohol, &c.—may be employed instead of pure water.

What I claim is—

- 10 1. In a Bunsen burner for liquid fuel, the combination with a receptacle for the fuel, a wick, an inner and an outer wick-tube, the latter passing right through the center of the receptacle, of a water-tube, arranged in the middle of the inner wick-tube, an evaporator-tube being fixed to the same, consisting of three compartments, the middle one of which may serve for generating, the upper one for superheating and the lower one for collecting the steam, nozzles for directing the steam into
15 the inner wick - tube, thereby producing a strong upwardly-directed current of air, and a flame-spreader for conducting the heat of the flame to the evaporator-tube, substantially as and for the purpose described.
- 20 25 2. In a Bunsen burner of the kind indicated, the combination with a receptacle for the fuel, a wick, an inner and an outer wick-tube, a water-tube arranged in the middle of

the inner wick-tube, an evaporator-tube co-operating with the water-tube and consisting of three compartments, nozzles for directing the steam from said evaporator-tube and a flame-spreader, of a central water-reservoir, a water wick-tube in the middle of the evaporator-tube and passing through the two lower compartment-partitions and bearing perforations near the lowest partition of the evaporator-tube, substantially as and for the purpose described.

30 3. In a Bunsen burner of the kind indicated the combination with a receptacle for the fuel and a water-reservoir, a wick-tube, a water-tube and an evaporator-tube coöperating with said water-tube and consisting of three compartments and bearing exit steam-nozzles, and a central water wick-tube bearing perforations, of a tube fitting exactly over the evaporator - tube and carrying a flame-spreader, substantially as shown and described.

40 45 50 In testimony whereof I affix my signature in presence of two witnesses.

RICHARD ADAM.
